Primary Examiner — Mary Ann Calabrese*(74) Attorney, Agent, or Firm* — Leanne Taveggia Farrell; Westman, Champlin & Kelly, P.A.(57) **CLAIM**

The ornamental design for an in-store marketing sign, as shown and described.

DESCRIPTION

FIG. 1 is a front view of one embodiment of the in-store marketing sign.

FIG. 2 is a left side view of the in-store marketing sign embodiment of FIG. 1.

FIG. 3 is a right side view of the in-store marketing sign embodiment of FIG. 1.

FIG. 4 is a back view of the in-store marketing sign embodiment of FIG. 1.

FIG. 5 is a top view of the in-store marketing sign embodiment of FIG. 1.

FIG. 6 is a bottom view of the in-store marketing sign embodiment of FIG. 1.

FIG. 7 is a front view of a second embodiment of the in-store marketing sign.

FIG. 8 is a left side view of the in-store marketing sign embodiment of FIG. 7.

FIG. 9 is a right side view of the in-store marketing sign embodiment of FIG. 7.

FIG. 10 is a back view of the in-store marketing sign embodiment of FIG. 7.

FIG. 11 is a top view of the in-store marketing sign embodiment of FIG. 7; and,

FIG. 12 is a bottom view of the in-store marketing sign embodiment of FIG. 7.

The dash-dot-dash lines in FIGS. 1-5 and 7-12 form no part of the claimed design for the in-store marketing sign. The dotted lines in FIGS. 1 and 7 represent scores that do form part of the claimed design for the in-store marketing sign. The solid angled line spaced apart from the bottom edge in FIGS. 1, 4, 7 and 10, represents a through cut that does form part of the claimed design for the in-store marketing sign.
